UNITED STATES PATENT OFFICE.

JAMES M. TRIGGS, OF HUNTINGTON, INDIANA.

DESIGN FOR A REGISTER.

49,102.

Specification for Design.

Patented May 23, 1916.

Application filed March 8, 1916. Serial No. 82,938. Term of patent 7 years.

To all whom it may concern:

Be it known that I, JAMES M. TRIGGS, a citizen of the United States, residing at Huntington, in the county of Huntington and State of Indiana, have invented a new, original, and ornamental Design for a Register, of which the following is a specification, reference being had to the accompanying drawing, forming a part thereof.

The figure is a perspective view of the register showing my new design.

I claim:

The ornamental design for a register, substantially as shown.

JAMES M. TRIGGS.
